UNITED STATES PATENT OFFICE.

RICHARD C. CONGDON, OF ATLANTA, GEORGIA.

APPARATUS FOR THE MANUFACTURE OF COAL-GAS.

1,099,639.

Specification of Letters Patent. Patented June 9, 1914.

Application filed March 14, 1914. Serial No. 824,640.

To all whom it may concern:

Be it known that I, RICHARD C. CONGDON, a citizen of the United States, and a resident of Atlanta, in the county of Fulton and State of Georgia, have invented certain new and useful Improvements in Apparatus for the Manufacture of Coal-Gas, of which the following is a specification.

The principal objects of the present invention are to prevent the accumulation of tar, pitch and lamp black inside the stand pipe; to scrub the gas in the stand pipe and thus lessen the burden on the balance of the works; to increase the capacity of the ex-
hausters, condensers and scrubbers; to rapidly cool the gas inside the stand pipe; to provide for disestablishing communication between the stand pipe and any retort or retorts, while the same is being charged or drawn, by means of a valve or valves which remain clean and operative; to obviate the expense, annoyance and work of cleaning the stand pipe at frequent intervals by manual or mechanical means, and to reduce the first cost of the installation while attaining the advantages above recited.

Broadly speaking and without disclaiming any novel features of the invention, the above objects are accomplished by the downward circulation of water, water gas tar or other fluid inside the stand pipe but without getting it inside the retort or retorts connected to the stand pipe in combination with the ascension of the gas through the stand pipe and with the arrangement of valves inside the stand pipe, so that they are kept clean by the descending fluid.

The invention will be claimed at the end hereof, but will be first described in connection with the embodiment of it chosen, from among other embodiments, for illustration in the accompanying drawings, in which—

Figure 1, is a front view with parts broken away and partly diagrammatically illustrating one form of apparatus embodying features of the invention. Fig. 2, is a sectional view, taken on the line 2—2 of Fig. 1 and drawn to an enlarged scale. Fig. 3, is a front view, with parts broken away, of another form of apparatus embodying a modification of the invention, and Fig. 4, is a side view with parts broken away of the apparatus shown in Fig. 3.

In the drawings 1, are the retorts of an apparatus for the manufacture of coal gas. 2, is a stand pipe in communication with each of the retorts and extending above and below the same. The gas from the retorts passes upward through the stand pipe 2 and is led off at the top thereof. The retorts communicate with the stand pipe 2 by means of branch pipes 3. There are means for discharging fluid or liquid, such as water, water gas, tar or other fluid, preferably in a divided state like spray, downward through the stand pipe. Within the stand pipe there are valves for establishing and dis-establishing communication between the interior of the retorts and the stand pipe. The descending liquid or fluid performs several important functions. It keeps the stand pipe clean, which is a matter of the utmost importance and value as will be understood by those skilled in the art; it scrubs and cools the ascending gas so that the rest of the apparatus, not shown, is relieved of this work, thus increasing the capacity of the plant and reducing the first cost of installation, and it keeps the valves clean so that they can be readily operated when it is necessary or desirable to establish or dis-establish communication between the retorts, or any of them, and the stand pipe. After descending through the stand pipe the liquid or fluid is collected in a trough or the like 4, into which the lower ends of the stand pipes dip so that the escape of gas at their lower ends is sealed off and prevented. At the top of the stand pipes the gas may be led off directly into an offtake pipe or collecting main 5, (Fig. 3) or it may be led off through a wash box or seal 6 (Fig. 1). The wash box is shown as consisting of a tank 7 and a cover or bell 8 with which the stand pipe communicates by way of a closed chamber 9 and connection 10. Within the chamber 9 there is space which receives fluid as at 11 and this fluid overflows down the stand pipe for the purpose already described. 12 is a pump, or the like, which lifts fluid from the trough 4, for example, to a reservoir 13 from which it flows by a valved pipe 14 to the space 11.

As shown in Fig. 3, the valved pipe 14 discharges into the top of the stand pipe, for example, against a baffle plate 15 and so the spray or downward circulation through the stand pipe above referred to is accomplished. The valves which are ar-

ranged in the stand pipe may be of any variety. As shown in Fig. 1, these valves are of the "flap" variety and are all alike so that a description will be given of one of them. The valve 16 is mounted upon one arm 17 of a rock-shaft 18 arranged within the stand pipe and the other arm 19 is arranged on the rock-shaft 18 but outside of the stand pipe so that it is accessible from the outside. 20 is a latch pivoted to a suitable bracket and adapted to be turned down over the arm 19 so as to hold the valve 16 in closed position and to be turned up clear of the arm 19 so as to permit the valve 16 to be opened.

The valves shown in Figs. 4 and 3 are arranged inside of the stand pipe and they are all alike, so that a description of one is sufficient. These valves 21 are slide valves 20 provided with handles 22 which extend through the wall of the stand pipe and they are slid in and out so as to cover and uncover the opening in the branch pipe 3. Of course, suitable stuffing boxes, or the like, 25 may be provided to prevent leakage at the points where the operating handles of the valves pass through the wall of the stand pipe and the various parts may be made of metal or other appropriate material.

It will be obvious to those skilled in the art to which the invention relates that modi-

fications may be made in details of construction and arrangement without departing from the spirit of the invention since the latter is not limited in regard to such matters.

What I claim is:

1. In apparatus for the manufacture of coal gas the combination of a retort, a stand pipe in communication with and extending above and below the retort, a valve arranged in the stand pipe for establishing and dis-establishing communication between the stand pipe and retort, means for withdrawing gas from the retort upward through the stand pipe, and means for supplying liquid downward through the stand pipe onto said valve and past the retort.

2. In apparatus for the manufacture of coal gas the combination of a stand pipe, a retort, a valve located in the stand pipe for establishing and dis-establishing communication between the stand pipe and retort, and means for introducing liquid down the stand pipe onto the valve to keep it clean, substantially as described.

In testimony whereof I have hereunto signed my name.

RICHARD C. CONGDON.
